UNITED STATES PATENT OFFICE.

HARRY P. DAVIS AND THEODORE VARNEY, OF PITTSBURGH, PENNSYLVANIA, ASSIGNEES TO WESTINGHOUSE ELECTRIC & MANUFACTURING COMPANY, A CORPORATION OF PENNSYLVANIA.

SUPPORTING STRUCTURE FOR TROLLEY-CONDUCTORS.

1,076,630.

Specification of Letters Patent.

Patented Oct. 21, 1913.

Application filed October 19, 1904. Serial No. 229,178.

To all whom it may concern:

Be it known that we, HARRY P. DAVIS and THEODORE VARNEY, citizens of the United States, and residents of Pittsburgh, in the 5 county of Allegheny and State of Pennsylvania, have invented a new and useful Improvement in supporting Structures for Trolley-Conductors, of which the following is a specification.

10 Our invention relates to apparatus for supporting and insulating overhead trolley conductors, and it has for its object to provide a simple, efficient and durable means for affording proper and satisfactory sup-

15 port for trolley conductors which are utilized for supplying high voltage energy to high speed railway equipments.

In the accompanying drawing, Figure 1 is a side elevation of a trolley pole provided 20 with conductor supporting and insulating devices which embody our invention. Fig. 2 is a detail, end elevation of a ring clamp for making connection between a messenger wire and an insulator. Fig. 3 is a side elevation of a supporting insulator and adjacent parts, a portion of the supporting arm upon which the said insulator and parts are mounted being also shown. Fig. 4 is an end elevation of the parts shown in Fig. 3, the 25 supporting arm being, however, shown in section.

The utilization of high voltage, alternating current energy for high speed railway service demands an overhead structure 30 which is more substantial in many respects and which provides a higher degree of insulation than is afforded by structures which have heretofore generally been used in railway work. Our present invention has been 35 designed and is specially well adapted for high tension, alternating current service, but it is equally well adapted, so far as operating conditions are concerned, to lower voltages and to direct currents as well as to 40 alternating currents.

The apparatus here shown as embodying 45 our invention is utilized in connection with a single line or set of trolley poles arranged along one side of a single-track road or between the two tracks of a double-track road. We have shown a single pole 1, to which is 50 rigidly fastened, at the proper height, one end of a horizontally projecting arm 2, this arm being shown in Figs. 1, 3 and 4 as an

iron or steel tube of annular cross-section. 55 Upon the arm 2, at a distance from the pole 1 corresponding to approximately the center of the track—provided a trolley is to be employed which is centrally located on the car,—we locate an adjustable insulating support 3, the insulator portion of which may be a tube or cylinder 4 of porcelain or other suitable non-conducting material having the requisite strength and insulating properties 60 and preferably having surface corrugations 65 that are formed by one or more circumferential grooves 5 and alternating annular projections or ribs 6. The insulator 4 may be mounted upon and securely cemented to a metal sleeve 7 that fits loosely upon the arm 70 2 and projects beyond each end of the insulator to form a substantially semi-cylindrical member 8 of a two-part clamping sleeve. The other part 9 of the clamping sleeve is provided with laterally projecting 75 arms 10, the outer ends of which are provided with sockets 11 to receive the ends of outwardly and downwardly projecting, U-shaped guard wires or rods 12 and with bolts 13 for clamping the ends of the wires or rods 80 12 in the sockets. The two parts 8 and 9 of the clamping sleeve are clamped together around the arm 2 by means of a U-shaped wire or rod 14, the ends of which project through suitable openings in the corresponding arms 10 and are provided with clamping nuts 15. By reason of the loose fit between the sleeve 7 and the arm 2, the device 3 may 85 be adjusted along the arm 2 to any extent desired, provided the clamping nuts 15 are loosened.

The trolley conductor 16 is supported at the desired distance above the track by means of a messenger cable 17 that is, in turn, supported from the insulators 4 so as 90 to assume catenary curves between the said insulators. The wires or rods 12 extend beneath and around the messenger cable and serve the double purpose of arresting the fall of the cable in case one of its supporting 100 devices breaks and of preventing injury to the insulator by the trolley in case it slips from the trolley conductor and flies upward under the action of the means employed for holding it in contact with the conductor. 105 The hangers 18 which connect the trolley conductor to the messenger cable may be of any character suited to the service and need

not be here described, since they do not constitute a part of our present invention. The messenger cable may be supported from each of the insulators 4 by means of a two-part hanger 19, which is clamped rigidly around the cable by means of bolts 20 and is provided with a double hook forming a ring 21 that is received in an opening 22 in a two-part ring clamp 23 of such diameter as to surround and fit the middle portion of the insulator 4. The two parts of the ring clamp 23 have a hinge connection at their lower ends by means of the ring 21 and their upper ends are respectively provided with an eye 24 and a hook 25 so that the device may be readily applied to the insulator and as readily removed when desired.

In order to securely support and brace the arm 2 in a horizontal position, we may provide a brace arm 26, the inner and lower end of which is securely attached to the pole 1, preferably by means of a hinge connection 27, as indicated, and the upper and outer end of which is provided with a tubular head 28 which surrounds the arm 2 and is locked thereto by a set-screw 29 or other suitable locking or clamping device.

In order to steady the trolley wire against lateral swing or vibration, we provide a rod 30, one end of which is attached to the trolley conductor by a suitable clamping device 31 and the other end of which is hinged to a clamping ring 23 which constitutes a part of an insulating and supporting device 3 that corresponds, in all respects, to the device 3 with which the arm 2 is provided, except that the U-shaped wires or rods 12 and the means for supporting them are omitted.

It will be understood that the device just described not only affords an effective safeguard against lateral swing or vibration of the trolley conductor, but also effectively insulates the conductor from the supporting brace arm 26.

Instead of connecting the steadyng rod 30 to the brace arm 23, it obviously might be connected to some other part of the supporting structure, if desired.

The details of the invention may be still further varied, as regards the form and dimensions of parts and also as regards the co-operating relations of certain of the elements, without departing from our invention.

We claim as our invention:

1. An overhead structure for electric railways comprising a pole, a laterally projecting arm provided with an insulator, a detachable clamp surrounding said insulator, a messenger wire or cable loosely supported from said clamp and U-shaped guard wires or rods that project outwardly and downwardly from the supporting arm around and beneath the messenger wire or cable. 55

2. An overhead structure for electric rail-ways comprising a pole, an arm projecting laterally therefrom and provided with an adjustable insulator, an auxiliary support for said arm, a messenger wire or cable supported from said insulator and U-shaped 60 guard wires or rods extending downwardly and outwardly from the supporting arm around the messenger wire or cable. 65

3. In an overhead structure for electric railways, the combination with a rod or bar, 75 of a porcelain tube having a sleeve which surrounds the rod or bar and to which the tube is cemented, said sleeve having projecting ends, clamps for fastening the projecting sleeve ends to the rod or bar, and U-shaped 80 rods that project outwardly and downwardly from said clamping devices.

4. In an overhead structure for electric railways, the combination with a pole, an arm projecting laterally therefrom, an insulator mounted upon said arm, an auxiliary support between said arm and the pole, a messenger wire or cable detachably suspended from said insulator, a trolley conductor suspended from said messenger wire or 90 cable, and U-shaped guard wires or rods that extend from the ends of the insulator around and beneath the messenger wire or cable. 85

5. In a catenary suspension for trolley wires, an arm, an insulator supported thereon, a guard for said insulator, a messenger wire supported by said insulator, a trolley wire, and means for suspending said trolley wire from said messenger wire. 95

In testimony whereof, we have hereunto 100 subscribed our names this 8th day of October, 1904.

HARRY P. DAVIS.
THEODORE VARNEY.
